UNITED STATES PATENT OFFICE.

JOSEF HAPPACHER, OF ESSEN, GERMANY, ASSIGNOR TO FRIED. KRUPP AKTIEN-
GESELLSCHAFT, OF ESSEN-ON-THE-RUHR, GERMANY.

CINEMATOGRAPHIC APPARATUS.

Application filed June 28, 1921. Serial No. 481,081.

To all whom it may concern:

Be it known that I, JOSEF HAPPACHER, residing at Essen, Germany, a citizen of the German Republic, have invented a certain 5 new and useful Improvement in Cinematographic Apparatus, of which the following is a specification.

The present invention relates to a cinematographic apparatus, in which the centering 10 of the image can be effected in a particularly suitable manner.

This object is obtained according to the 15 present invention by the fact that the single-toothed wheel of the apparatus can be rocked about the axis of the Maltese cross and that there is interposed between the single-toothed wheel and the shutter a regulating apparatus which when the single-toothed wheel is rocked, preserves the 20 synchronous running between this latter and the shutter.

The invention will be described with reference to the accompanying drawings which 25 show an embodiment of the subject-matter of the invention by way of example together with a modification.

In these drawings:

Fig. 1 is a vertical section of the first example, certain parts being broken away,

Fig. 2 is a section on the line 2—2 of Fig. 1, seen from above, certain parts being broken away,

Fig. 3 is an axial longitudinal section of 35 a detail on a larger scale,

Fig. 4 is a section on the line 4—4 of Fig. 2, seen from the left,

Fig. 5 is a section corresponding to Fig. 2 of a modification of the first example, and

Fig. 6 and 7 show on a larger scale two 40 details of Fig. 5, one of the details (Fig. 7) being shown in section.

In the casing A of the cinematographic apparatus is mounted the driving shaft B, on which is fixed a cord pulley b¹ coupled to the driving motor (not shown in the drawings) and a double gear wheel b² b³ (see Fig. 1 and 2). The wheel b² is constructed in the form of a worm wheel and engages with a worm wheel c¹, which is fixed on a shaft C mounted vertically in the casing A. Into the worm wheel c¹ gears a worm d¹ (see Fig. 2), which is fixed on the shaft D carrying the shutter d². To the shaft C are also rigidly connected two other worm wheels c² and c³. Of these two wheels the upper one,

c², gears with a worm wheel e¹, which is mounted on the shaft E carrying the transmitting sprocket wheel e², while the lower worm wheel c³ gears with a worm wheel f¹, which is fixed on the shaft F which carries 60 the receiving sprocket wheel f² and is provided with a handle for driving the machine by hand (see particularly Fig. 4).

The wheel b³ is constructed in the form of a spur wheel and gears, in the ratio of transmission of 1:1, with a gear wheel G, which has considerably wider teeth than the gear wheel b³ and is rigidly connected to a sleeve G¹. This sleeve G¹ is mounted to rotate and also move longitudinally on a shaft H, which engages by means of two oppositely situated partial screw threads h¹, in two grooves g² in the sleeve G¹ (see Fig. 2 and 3). The shaft H is mounted eccentrically 70 with respect to a rotatable member J mounted in the casing A. This rotatable member J can be rocked about the driving shaft B by means of a pinion shaft K having a milled head h¹ and the pinion k² of which 75 gears into a toothed sector i¹ provided on the rotatable member J.

The sleeve G¹ is enclosed in a sleeve M, which can be displaced axially in a sleeve-shaped guide i² on the rotatable member J, but is prevented from rotating by a pin i³ 85 which is fixed in the guide i² and engages in an axial longitudinal groove m¹ in the sleeve M (see Fig. 1). In the said sleeve M is provided a helical groove m², in which a partial screw thread a¹ rigidly fixed to the casing A engages. On the shaft H there is fixed the single toothed wheel h². This wheel engages with the Maltese cross n¹, which is mounted on a shaft N mounted coaxially with the driving shaft B and carrying the middle sprocket wheel n², (see Fig. 2). The film P, which is indicated by dot and dash lines in Fig. 4, runs over the upper sprocket wheel e², the middle sprocket wheel n² and the lower sprocket wheel f² behind the gate a² which is mounted on the casing A and cooperates with the shutter d² 95 in the well known way.

When the machine is working normally 100 the following operations take place:

The driving shaft B, which is driven by the motor (not shown in the drawings) through the cord pulley b¹, imparts its rotation through the medium of the gear wheel b³ to the gear wheel G and also to the sleeve 110

G¹, to the shaft H (coupled to these parts by the partial screw threads h¹ which engage in the grooves g²) and to the single toothed wheel h². The Maltese cross n¹, and 5 with it the sprocket wheel n², and the film P will be rotated intermittently by the single toothed wheel h².

On the other hand the rotation of the driving shaft B will be transmitted by the 10 worm wheel b², through the worm wheel c¹ to the vertical shaft C, which, through the medium of the gears c² c¹ E, c³ f¹ F and c⁴ d¹ D drives the upper sprocket wheel e², the lower sprocket wheel f² and the shutter d².

15 Should a wrong adjustment of the image take place during the working of the machine and the advance movement of the film P be consequently affected so that its adjustment relatively to the gate a² is 20 regulated again, the pinion shaft K is rotated by the aid of the milled head L¹. The rotation of the pinion shaft K causes in consequence of the engagement of the pinion k² in the toothed sector i¹ a rocking 25 movement of the rotatable member J and also of the sleeve i². During this rocking movement of the rotatable member J the gear wheel G, which is mounted eccentrically with respect to the axis of rotation 30 of the rotatable member J, will be displaced by the partial screw thread a¹ which engages in the groove m² of the sleeve M, the latter being prevented from rotating by the gear members i³ m¹. In addition to 35 this displacement however the gear wheel G is simultaneously rotated relatively to the shaft H and the single toothed wheel h² by the partial screw thread h¹, the pitch of the partial screw thread h¹ being so selected 40 that the gear wheel G is rotated through the same angle through which the rotatable member J is rocked. When therefore the rotatable member J is rocked, an increased or a reduced speed will be imparted to the 45 gear wheel G and moreover in such a measure that the shaft H, the single-toothed wheel h² and the shutter d² always run at the same speed as the driving shaft B. Were this not so, the synchronism between 50 the mechanism for feeding the film and the shutter d² would be disturbed. The rocking of the rotatable member J also causes however a change in the fundamental 55 position of the Maltese cross n¹, such fundamental position being changed by the angle through which the rotatable member J is rocked. By this means the feed of the film will be so increased or reduced that a complete 60 image appears at the gate a² again.

In the modification of the first example which is shown in Fig. 5 to 7 the gear wheel G which engages with the gear wheel b² is mounted so that it cannot move longitudinally, but can rotate freely on the shaft H. The partial screw threads lettered

h¹ in the first example are placed on the extended hub g² of the gear wheel G and are lettered g⁴. The partial screw threads g⁴ engaged in corresponding grooves g² in the sleeves G¹, which is separated from the gear wheel G (see particularly Figs. 6 and 7). The sleeve G¹ is displaceably mounted on the shaft H and has also two other grooves g⁵ situated opposite each other and running axially, with which two driving pins h³ fixed on the shaft H engage. By means of the sleeve G¹ the gear wheel G is therefore connected to the shaft H in such a way that when the sleeve G¹ moves axially, mutual rotation of the gear wheel G and the shaft H takes place, as in the arrangement shown in Figs. 1 to 4.

In other respects, the type of construction shown in Figs. 5 to 7 is the same as that of the type of construction shown in Figs. 1 to 4. The working of the arrangement shown in Figs. 5 to 7 will be understood at once after the description which has been given in connection with Figs. 1 to 4.

90 In comparison with the arrangement shown in Figs. 1 to 4 the construction last described has the advantage that the gear wheel G, owing to the fact that it is incapable of moving longitudinally, may be provided with teeth of normal width and is also subjected to less wear.

In all constructions above described, the centering of the image is thus attained by the 100 fact that by the rocking of the rotatable member J and therewith of the single-toothed wheel h² the fundamental position of the Maltese cross n¹ is changed and the film thereby adjusted. In this case the regulating apparatus which is interposed between the single-toothed wheel h² and the shutter d², namely h¹ G¹ M a¹ in Figs. 1 to 4, g⁴ G¹ M a¹ in Figs. 5 to 7, solves the problem of maintaining the relative angular 105 position between the shutter d², which is not additionally rotated, and the single-toothed wheel h², that is to say, of maintaining the synchronism of these two parts 110 which is necessary for correct working.

115 Claims:

1. In a cinematographic apparatus, a film 120 drive including an intermittent driving member, a shutter, said film drive and shutter operating synchronously, the intermittent driving member of said film drive including a single-toothed wheel, a shaft therefore, an intermediate gear wheel interposed between the shaft of the single-toothed wheel and the main driving shaft of the film drive, a displaceable member for coupling 125 said intermediate gear wheel to the shaft of the single-toothed wheel, a movement of said displaceable member causing a mutual rotation between said last mentioned shaft and said intermediate gear wheel, means for 130

adjusting the single-toothed wheel and means whereby an adjustment of said single-toothed wheel causes a displacement of said displaceable member.

2. In a cinematographic apparatus, a film drive and a shutter, said film drive and shutter operating synchronously, said film drive including a main drive shaft, a single-toothed wheel and a shaft therefor, an intermediate wheel mounted on said last mentioned shaft and driven by said driving shaft, a displaceable member for coupling said intermediate wheel to the shaft of said single-toothed wheel, a movement of said displaceable member causing a mutual rotation between the shaft of said single-toothed wheel and said intermediate wheel, a regulating device for rocking said single-toothed wheel and means actuated by this adjustment for causing a displacement of said displaceable member.
3. In a cinematographic apparatus of the class described a film drive embodying a main drive shaft and a single-toothed wheel, a shaft for said single-toothed wheel, an intermediate wheel on said shaft and driven by said main driving shaft, a displaceable member for coupling said intermediate wheel to the shaft of said single-toothed wheel, a displacement of said displaceable
- member causing a mutual rotation between the shaft of said single-toothed wheel and said intermediate wheel, means for causing the displacement of said displaceable member comprising a partial screw-thread rigidly mounted in the casing of the cinematographic apparatus, said displaceable member being formed with a recess and means for rocking said single-toothed wheel and for causing said last mentioned means to displace said displaceable member.
4. In a cinematographic apparatus, a film drive and a shutter, said film drive and said shutter operating synchronously, said drive embodying a single-toothed wheel, a shaft therefor, an intermediate wheel on said shaft and driven by the main driving shaft of the film drive, a displaceable member rigidly connected to said intermediate wheel, said displaceable member operating to couple said intermediate wheel to the shaft of said single-toothed wheel, a displacement of said displaceable member causing a mutual rotation between the shaft of said single-toothed wheel and said intermediate wheel and means for displacing said displaceable member.

The foregoing specification signed at Essen, Germany, this 23rd day of May, 1921.

JOSEF HAPPACHER.
